UNITED STATES PATENT OFFICE.

OLE S. JOHNSON, OF ST. PAUL, MINNESOTA.

DOMESTIC WATER-HEATER.

1,211,858.

Specification of Letters Patent.

Patented Jan. 9, 1917.

Application filed March 9, 1915. Serial No. 13,292.

To all whom it may concern:

Be it known that I, OLE S. JOHNSON, a citizen of the United States, residing at St. Paul, in the county of Ramsey and State of Minnesota, have invented new and useful Improvements in Domestic Water-Heaters, of which the following is a specification.

This invention is an improved boiler for heating water for domestic use and also for other analogous uses, the object of the invention being to provide an improved boiler of this class which utilizes a far greater proportion of heat units than heretofore in the heating of the water, which minimizes the loss of heat by radiation, which utilizes heat units passing from the fire box for maintaining the heat in the hot water feed pipe, and which is adapted to be readily assembled and disassembled to facilitate installation and repairs.

The invention consists in the construction, combination and arrangement of devices hereinafter described and claimed.

In the accompanying drawings:—Figure 25 1 is a vertical central sectional view of a domestic water heater constructed in accordance with my invention. Fig. 2 is a detail sectional view, on a larger scale, of the lower portion of the heater and its connections. 30 Fig. 3 is a transverse sectional view on the plane indicated by the line *a—a* of Fig. 1. Fig. 4 is a similar view on the plane indicated by the line *b—b* of Fig. 1.

In the embodiment of my invention I 35 provide an upright central tank 1 the outer wall 2 of which is made of galvanized sheet iron or other suitable material. The top 3 of the tank is concavo-convex, cross sectionally, with the convex side uppermost, and is riveted to the wall 2. The bottom 4 is also concavo-convex, cross sectionally, with the concave side lowermost. The bottom is arranged in the lower end of the tank, is riveted to the lower portion of the wall as at 40 5 and has a central opening 6 which opens into the lower end of a screw shaped fire box 7 whereby the fire box is formed with spiral convolutions 8 which resemble screw threads. A vertical tubular flue 9 is arranged in the 45 center of the tank, its upper end extending through and slightly above an opening in the top 3 and its lower end being suitably connected to the upper end of the fire box. A boiler 10 which is also screw-shaped and 50 is of somewhat less diameter than the fire

box is arranged in the latter and spaced from the corrugated wall thereof, the boiler being also provided with corrugations 11 which constitute its screw convolutions and said corrugations of the boiler by reason of 60 their spaced relation to the spiral corrugations of the fire box forming a tortuous annular passage 12 between the boiler and the fire box and of the boiler forming baffles in the 65 opposing walls thereof as will be understood.

A hot water pipe 13 passes upwardly through the center of the flue 9 and has its lower end secured to the top of the boiler. The said hot water pipe is here shown as 70 provided with an elbow 14, above the tank and with a horizontal branch 15 connected to said elbow and held by a bracket 16. By first disconnecting the pipe 13 from the elbow 14 the pipe and the boiler can be removed from the tank, it being necessary to 75 also turn the boiler to afford screw like connection and permit the withdrawal of the boiler from the lower end of the fire box.

A cold water feed pipe 17 is connected to 80 a suitable water system which leads down into the tank through the top or cover 3 and terminates at its lower end about eighteen inches, in brackets, above the fire box. The boiler is supplied with water from 85 the tank by a pipe 18 which leads from the bottom of the tank to the bottom of the boiler and is here shown as provided with an elbow 19, a T 20 and a faucet 21, the latter enabling water to be drawn or drained 90 from the tank when desired.

A suitable gas, gasoline or kerosene burner 22 is employed which is arranged below the boiler and the fuel supply pipe of which is indicated at 23. This burner may be of any 95 suitable type within the scope of my invention.

I also provide a worm baffle 23' which is arranged in the flue 9 and around the hot water pipe 13. This baffle may also be withdrawn from the tube 9 when desired. A supply flue 24 connects the upper end of the flue tube 9 with a chimney or other flue for carrying off the heated products of combustion.

Owing to the location of the fire box and the boiler within the lower portion of the body of the water tank, the heated air from the burner in passing spirally around the screw shaped boiler and between the same 100 105 110

and the similarly shaped fire box not only serves to heat the boiler so as to highly heat the water therein but also serves to heat the water in the lower portion of the tank to some extent so that the water is partially heated before it passes from the tank to the boiler. Moreover such arrangement of the fire box and the boiler within the tank utilizes the heat that would be radiated from the fire box wall if the latter were exposed and moreover this construction is highly advantageous in that it does not effect the heating of the tank and hence the latter does not radiate heat, which is highly objectionable in kitchens and other like places, especially in warm weather. The baffle worm causes the escaping heated air and products of combustion to pass up spirally in the pipe 9 and around the pipe 13 thereby maintaining the heat of the latter.

Having thus described my invention I claim:

In a device of the kind described, in combination an upright central tank, a concavo-convex bottom in said tank having its con-

cave side lowermost, a screw shaped fire box secured to the bottom and having its convolutions of uniform diameter, said fire box terminating, at its upper end, in a tubular portion, a vertical tubular flue projecting 30 into said tubular portion, a screw shaped boiler having its convolutions of uniform diameter disposed concentrically in said fire box, a nipple formed at the upper end of said boiler, a hot water pipe secured in said nipple, a worm baffle resting upon said nipple and extending around the length of said hot water pipe, an inlet pipe projecting through said bottom and having a vertical pipe connection secured in the bottom of 40 said boiler, and a supply pipe extending into said tank and secured to the upper end thereof.

In testimony whereof I affix my signature in presence of two witnesses.

OLE S. JOHNSON.
